UNITED STATES PATENT OFFICE.

GEORGE H. GILMAN, OF BELMONT, MASSACHUSETTS.

ROCK-DRILL SUPPORT.

Application filed July 30, 1921. Serial No. 488,598.

My invention relates to material working machines and particularly but not exclusively to those for drilling rock.

My invention will be best understood 5 from the following description when read in the light of the accompanying drawings showing a specific embodiment of my invention selected for illustrative purposes while the scope of my invention will be more particularly pointed out in the appended claims.

In the drawings:—

Fig. 1 is an elevation of a breast stopper and its mounting;

Fig. 2 is a section on the line 2—2 of 15 Fig. 1;

Figs. 3 and 4 are sections respectively on the lines 3—3 and 4—4 of Fig. 2;

Fig. 5 is a section on the line 5—5 of 20 Fig. 3; and

Fig. 6 is a section on the line 6—6 of Fig. 5.

Referring to the drawings I have shown a tool 1 and its actuator 3 and although these may be of any suitable type I have indicated the tool as a rock drill steel and its actuator as a fluid pressure operated hammer. The actuator I secure to any suitable support herein exemplified as the mine column arm 5. For mounting the actuator on the arm I have herein provided means for feeding the actuator relatively to the rock and for moving it transversely to the direction of drilling of the tool, or in other words with regard to this latter motion, 25 with the machine in the position illustrated by the drawings I have provided means for raising and lowering the actuator.

As illustrated the feeding means for the actuator comprises a shell 7 which, as will be understood by those skilled in the art, affords guideways for receiving the guides 9 carried by the actuator while for moving the guides along the guideways a feed screw or other appropriate means, not shown, may be provided. As the actuator and feeding mechanism do not form a part of my present invention the same will only be described with particularity sufficient to explain how they are applied to my present invention.

For securing the parts to the arm 5 I have shown a split sleeve comprising the semi-cylindrical half-sections 11 and 13 which fit the exterior surface of the arm and which are adapted to be clamped thereto by means of pairs of bolts 14 extending through opposite ends of said half-sections.

As illustrated integrally formed with the half-section 13 and transversely thereto is a sleeve 15 having a cylindrical bore 17 in which is retained the exteriorly-cylindrical hollow post 19, the construction providing that the members 15 and 19 are telescopically arranged in such manner that the member 19 may both slide and rotate in the bore 17.

The sleeve 15 is herein provided at its lower end as viewed in the drawings with a cover 21 attached to the sleeve by means of the bolts 23 and provided with a perforation 25 in which is rotatably mounted the shank 27 of the screw 29. As illustrated the screw interiorly of the cover is provided with a thrust-collar 31 which rests on the interior surface of the cover and exteriorly of the cover the shank of the screw has keyed thereto a hand wheel 33. Interiorly of the sleeve I have shown on the screw a nut 35 prevented from rotating relatively to the sleeve by means of wings 37 slidably fitting ways 39 formed on opposite sides of the bore 17. As illustrated the screw extends upwardly into the hollow post which is provided with an interior annular rib 41 affording a shoulder resting on the top surface of the nut. The grooves 39 formed in the surface of the bore 17 as shown terminate in shoulders 43, which serve as stops to limit the upward travel of the nut. As will be obvious, by turning the hand wheel 33 the screw 29 may be rotated to cause the nut to move along the screw and thereby cause the post 19 to be raised and lowered relatively to the sleeve 15.

It will be observed that the construction above described does not prevent the post from swivelling in the sleeve and that this swivelling permits the drill steel to operate in different directions. Herein for locking the post and the sleeve together the latter is cut away at an intermediate portion thereof to provide a recess 45 extending for about half the circumference of the sleeve, which recess receives the clamping member 47. At each side of one end of the recess I have shown the sleeve as provided with a pair of perforated ears 49 through which extends a bolt 51 providing a pivot for the clamping member 47. At one end the clamping member is shown as provided with a perforated boss 53 and at its other end with a perforated boss 55, the perforation

of the former receiving the pin 51 and the perforation of the latter, the bolt 57. The bolt extends through the perforation 59 of the sleeve and is provided at its end opposite the clamp with the polygonal head 61 loosely fitting a similar shaped recess 63 in the interior surface of the half-section 13. As shown at its opposite end the screw carries the hand wheel 65. As will be obvious by means of the hand wheel the clamp may be drawn against the post to prevent swivelling of the latter in the sleeve 19.

Herein at its upper end the post has integrally formed therewith a head 67 which provides an annular shoulder 69, the latter in the position of parts illustrated by the drawings resting on the top of the sleeve 15 and determining lower limit of movement of the post relatively to the sleeve. The head supports the shell 7, and for this purpose is shown as provided with a surface 71 on which the bottom of the shell rests. As illustrated for clamping the shell to the head at different points lengthwise of the shell, the latter is provided at the lowermost portion of its respective sides with the oppositely beveled surfaces 73 and 75, the former contacting with the correspondingly shaped beveled surface formed on the upstanding portion 77 of the head. On the opposite side of the head from the upstanding portion 77 and positioned below the surface 75 is shown a surface 79 beveled in the opposite direction to the surface 75 and for engaging both of these surfaces I herein provide a clip 81 having correspondingly beveled surfaces. The clip and head as shown are provided with aligned perforations through which extends a bolt 83 by means of which the clip 40 may be drawn firmly against the head and shell to secure these parts rigidly together.

As one example of the use of my invention, the hole may be drilled with the actuator in its elevated position and after the hole is drilled the operator may move the actuator away from the rock by means of the feeding mechanism far enough to withdraw the shank of the drill steel from the chuck of the actuator, whereupon the actuator may be lowered to the position shown by the drawings and the drill steel pulled from the hole without interference by the actuator.

Although I have described for purposes of illustration one specific embodiment of my invention, it is to be understood that I am not limited thereto but that wide deviations may be made therefrom and parts described omitted or other parts substituted therefor without departing from the spirit of my invention.

Claims:

1. In a drilling machine, a shell for a tool actuator, a member carrying said shell and arranged to be clamped in adjusted positions longitudinally of said shell, a support

for said machine, and a connection between said member and support, a screw for raising and lowering said member relatively to said support, and a nut fixed against rotation cooperating with said screw and member for 70 permitting said member to rotate about the axis of said screw without being moved by said screw.

2. The combination with a tool actuator of a supporting post therefor, means providing a guide for guiding said post transversely to the direction of working of said tool, a nut and screw for moving said post along said guide, said post being rotatable relatively to both said guide and nut, and said nut being fixed against rotation relatively to said guide.

3. A mounting for a tool actuator comprising a sleeve, a member swivelled in said sleeve and carrying said actuator transversely positioned relatively to said sleeve, a nut and screw for moving the swivelled member relatively to said sleeve, and means permitting said swivelled member to rotate relatively to said nut.

4. A mounting for a tool actuator comprising telescopically arranged relatively slidable and rotatable members, a screw for causing such sliding, means for attaching one of said members to a support, a nut 95 mounted in sliding but non-rotatable relation to said last mentioned member, means for attaching the other member to a drill actuator transversely thereto, and said last mentioned member being rotatable relatively to 100 said nut.

5. A mounting for a tool actuator comprising a sleeve having means for attachment to a support, a member carried by said sleeve and carrying at one end thereof means for attachment to said actuator, means for clamping said member and sleeve together, a screw carried by said sleeve, a nut carried by said screw for causing sliding of said member in said sleeve, and said nut being non-rotatable relatively to said sleeve and said member being rotatable relatively to 110 said nut.

6. In a mounting for a tool actuator, a sleeve member having a cylindrical bore, a member mounted in said bore in such wise that said members are slidably and rotatably relatively movable, means for attaching one of said members to a support, means for attaching the other of said members to a tool actuator transversely thereto, a screw carried by one of said members for causing relative sliding of said members, a nut on said screw splined to said sleeve member, the other of said members resting upon and being rotatable relatively to said nut, and means carried by one of said members for clamping the other thereto to prevent relative rotation between the members.

7. The combination with a drill steel and 120

its actuator, of a mounting for supporting said actuator for longitudinal feeding movement, means providing a swivel for attaching said mounting at a point intermediate 5 the travel of the actuator to a support, and means including a screw and nut for moving said mounting transversely to the travel of said actuator and permitting swivelling without effecting actuation by said screw 10 and nut.

8. A rock drill, having in combination, a hammer drill having a removable drill steel,

a feed shell on which said hammer drill is slidably mounted, a pair of telescoping members one of which is attached to said feed 15 shell and the other to a support, a nut splined to one member and supporting the other member, a rotatable non-longitudinally movable screw for moving said nut, and means for clamping one member to the 20 other.

In testimony whereof, I have signed my name to this specification.

GEO. H. GILMAN.
